UNITED STATES PATENT OFFICE.

CLARENCE P. JOHNSON, OF NEWTON, MASSACHUSETTS.

DISPLAY STAND FOR MERCHANDISE.

Application filed July 23, 1926. Serial No. 124,531.

The invention relates to display stands for merchandise and especially those for the display of candy in boxes.

The essential object of the invention is to provide a display stand of simple construction yet neat and attractive in appearance; one into which a filled box with its cover removed can conveniently be placed and its contents displayed to advantage, at the same time being covered and protected.

Among the further objects of the invention are to provide a display stand capable of receiving a box only of a determinate size; to provide a display stand of a collapsible or knockdown character but one capable of being quickly and easily assembled; one that is especially fitted for display on the top of a counter or showcase, and also one that is capable of displaying the cover of the box as well as its contents. In candy boxes especially the cover is usually made very attractive in appearance, and my purpose is to provide a stand capable of showing this cover to advantage at the same time the contents of the box are being displayed.

The invention can best be seen and understood by reference to the drawings, in which—

Figure 1 is a view in perspective of the stand;

Fig. 2 is a section thereof, and

Fig. 3 is a view in perspective of the stand with box body and cover arranged therein for purposes of display.

Referring to the drawings:—

1 represents the base of the stand. This base is in the nature of a tray made of relatively thin sheet metal and is generally rectangular in form. The front, back and opposite side edges of the base are finished by bending the metal adjacent the edges back upon itself. Such bending of the metal along the front and back functions also for pivotally retaining the front and back frames 2 and 3 respectively, which together with the base give form to the device when assembled, these front and back frames then meeting along their top marginal edges. Thus the stand is generally triangular in form and presents a beveled front.

The front frame 2 is generally rectangular in form and consists simply of a stiff bent wire of which 4 is its bottom section; 5 is its top section, and 6, 6 respectively its side sections. The bottom section 4 is pivotally retained by the flange 7 which is the part turned back to give finish to the front edge of the base, the entire frame 2 accordingly being capable of freely turning on the base at this point. The frame 2 in its dimensions is made to bear a certain relation to the box body designed to be placed in the stand and the contents of which are to be displayed. Its width or the distance between its side sections 6, 6 is somewhat longer than the length of the box body, while the length of the frame or distance between its top and bottom sections is appreciably longer than the width of the box body, the frame in fact having a certain determinate length and width as will later be more fully explained.

Extended across the face of the frame 2 at the bottom of the frame is a panel 8. This panel is of sheet metal and it is firmly bound to the frame by bending its opposite ends around the side wire sections 6, 6 of the frame and clinching, while the bottom edge 9 of the panel is extended around the joint between the frame and the front edge of the base covering this joint.

Above the panel 8 the space enclosed by the frame lying between its side sections 6, 6, and between its top section 5 and the panel 8, is occupied by a glass 10 which is arranged to lie within the plane of the frame. The bottom edge of the glass fits within a groove 11 formed by bending the metal along the top edge of the panel 8 back upon itself and then forward. The groove thus formed lies substantially within the plane of the frame 8 and receives the bottom edge of the glass, securely holding it in place. Along its opposite sides the glass is bound to the respective side wire sections 6, 6 of the frame by metal strips 12 bent around the respective side wire sections and clinched onto the glass. Along its top the glass is bound by a metal strip 13 which is substantially like the strips 12 along the sides.

The strip 13, however, does not extend around the top wire section 5 of the frame, but lies just beneath it leaving this wire section exposed, for a purpose later to be explained. That portion of the strip 13 which overlies the face of the glass at the top is extended at either end to cross the side wire sections 6, 6 of the frame, and is then turned to form ears 14, 14 in which are formed holes 15. These ears assist in the support of the back frame 3 as will later be explained.

In the manner just explained, the bottom metal panel 8 and the various metal strips 12, 12 and 13 not only secure the glass to the frame, but also impart a finish around the glass. They also act to form a frame or edging to the top edge of the box when arranged back of the glass for displaying its contents through the glass when the box is in place in the assembled device. In other words, as may be seen by reference to Fig. 3, the box A is arranged on edge to lie in an inclined position resting upon the base and bearing all around its top edges against the edging around the glass. The relation or relative size of the glass to the top area bound by the top edges of the box is such that the top edges of the box will lie back of, and be concealed by the top edge of the panel 8 together with the various metal strips bound to the glass, these acting to form a frame around the top edge of the box the contents of which are displayed through the glass.

The back frame of the device is of wire consisting preferably of a single wire bent to provide various parts or sections serving different purposes. In order that the back frame may be pivotally mounted to turn on the back edge of the base in a manner similar to the pivotal mounting of the front frame on the front edge of the base, the back frame is provided at its bottom with separate aligned sections 16, 16. These sections of the wire are arranged to turn in hinge members 17 formed from parts of the base turned back along its rear edge to give finish to the edge, as previously described. The sections 16 of the wire thus arranged to turn are located at the opposite side ends of the base, and each of the sections 16 is extended laterally beyond the hinge member in which it is arranged to turn. By bending the wire and extending it from the outer ends of the two sections 16 the frame is provided at either side with sections 18, respectively, having turned ends 19 adapted to fasten into the holes 15 formed in the ears 14 at the top of the front frame, to the end that the two frames may be combined in the assembling of the device and the front frame be held by the back frame acting as a support in an upright inclined position. By bending the wire and extending it from

the inner ends of its two sections 16 the frame is provided with sections 20 connected at their outer ends by a section 21 which lies spaced from the front frame, the combined sections 20 and 21 forming a back support 70 for the box body when located in the assembled device resting on the base as previously described.

In assembling the stand the box body is inserted between the front and back frames 75 resting cornerwise upon the base with its top open end faced by the sight in the glass and framed by the edging around the glass. Then on connecting the two frames the back support movable with the back frame is 80 brought into engagement with the back of the box body thereby holding it securely in place. The box body may also be inserted into the stand or removed from it after the front and back frames have been connected 85 or assembled and without disassembling these frames. This is done by inserting the box body through the opening left between the two side sections 18 of the back frame and between the top cross section 21 of the 90 back support and the top section 5 of the front frame. This space is just sufficient to admit of the entry of the box body. However inserted, the stand is especially adapted for the display of a box body only 95 of a determinate size inasmuch as the back support for the box body when in place fixed as it is to the back frame and movable with it, leaves only a determinate space between it and associated assembled parts 100 for receiving a box body of a determinate size.

Referring now to those parts of the device which relate to the support and display of the cover in the assembled device: In this 105 connection it will first be observed that with the box body in place in the assembled device it will extend through and above the plane of the back frame and its top side 23 will incline backward from the top of the front 110 frame substantially at right angles thereto.

The side thus extending is taken advantage of to provide a rest for the cover which rests along its side 24 upon the side 23 of the box body. When so resting the cover will 115 extend in line with the box body, substantially in continuation thereof and the top of the cover will lie substantially in the plane of the glass in extension thereof, and accordingly any decorative matter upon 120 the top of the cover will be displayed at the same time that the contents of the box lying below it are displayed. The box cover is held in this position by means of clips 25 consisting of bent strips of metal hinged to 125 turn upon the top wire section 5 of the front frame and bent back upon themselves to form sockets in which the side 24 of the box cover resting on the box body is adapted to fit and be held by the clips.

The means provided for the retention of the box cover for display purposes is such that the cover may be altogether omitted if desired, when the means for retaining the 5 cover will not detract from the appearance of the assembled stand.

Upon disassembling the stand and unlocking its front and back frames these frames together with the clips for retaining the 10 cover will all collapse and lie flat substantially parallel with the base, making a very compact package.

Having thus fully described my invention, I claim and desire to secure by Letters 15 Patent of the United States:—

1. A collapsible display stand having in combination a base, a front frame pivoted to the base and movable to occupy an upright backwardly-inclined position with relation 20 to it, said front frame having a sight in it, a back frame pivoted to the base and movable to connect with the front frame for supporting said front frame in its upright inclined position as aforesaid, said frames being arranged whereby a box body may be located between the two frames when connected resting cornerwise on the base with upward extension by the front frame in the rear thereof back of the sight therein, 25 and a back support movable with the back frame to have bearing against the back of the box body for holding it in place when positioned as aforesaid.

2. A collapsible display stand having in combination a base of metal plate, a front frame substantially rectangular in form pivoted to the base and movable to occupy an upright backwardly-inclined position with relation to said base, the front frame 40 having a sight in it, a back wire frame pivoted to the base with sections connecting with the front frame for supporting said front frame in its inclined position as aforesaid, said frames being arranged whereby a box body may be located between the two frames when connected resting cornerwise on the base with forward extension by the front frame in the rear thereof back of the sight therein, and a back support for the 45 box body when positioned as aforesaid comprising a bent wire integral with the back frame.

3. A collapsible display stand having in combination a base, a front frame pivoted to the base and movable to occupy an upright backwardly-inclined position with relation to said base, the front frame having a sight in it, a back frame pivoted to the base and movable to connect with the front frame for 55 supporting said front frame in its inclined position as aforesaid, said frames being arranged whereby a box body may be located between the two frames when connected resting cornerwise on the base with upward 60 extension by the front frame in the rear

thereof back of the sight therein, means for connecting the two frames, and a back support movable with the back frame to have bearing against the box body for holding it in place when said frames are connected. 70

4. A collapsible display stand having in combination a base, a front frame pivoted to the base and movable to occupy an upright backwardly-inclined position with relation to said base, the front frame having a sight in it, a back frame pivoted to the rear of the base and extending to connect with the front frame for supporting said front frame in its upright inclined position as aforesaid, said frames being arranged whereby a box 80 body may be located between the two frames when connected resting cornerwise on the base with upward extension by the front frame in the rear thereof, and a back support for the box body when positioned as aforesaid movable with the back frame, the top of said back support being spaced from the front frame whereby the box body may be inserted into place between the connected frames or removed therefrom by passage 85 over said support.

5. A collapsible display stand having in combination a base, a front frame pivoted to the base and movable to occupy an upright backwardly-inclined position with relation to said base, the front frame having a sight in it, a strip extending along the top of the front frame with ends turned around the opposite sides of said frame adjacent the top thereof, a back wire frame pivoted to the base at the rear thereof and comprising side sections extending to connect with the turned ends of said strip on the front frame for supporting said front frame in its upright inclined position, said frames being 100 arranged whereby a box body may be located between the two frames when connected resting cornerwise on the base with upward extension by the front frame in the rear thereof back of the sight therein, and a back support movable with the back frame to have bearing against the box body for holding it in place when said back and front 105 frames are connected as aforesaid.

6. A collapsible display stand comprising in combination a front frame having a sight in it, means whereby a box body may be retained to lie back of said frame faced by the sight therein and one side of the box body will incline backward from the top of the front frame at substantial right angles thereto, and clip-forming means connected to the stand at the top of the stand to receive and retain one side of the box cover superposed upon said one side of the box body whereby the cover will be retained to lie for purposes of display above and in substantial continuation of said body. 120

7. A collapsible display stand comprising in combination a front frame having a 130

sight in it, means whereby a box body may be retained to lie back of said frame faced by the sight therein and one side of the box body will incline backward from the top 5 of the front frame at substantial right angles thereto, and clip-forming means secured to the front frame at the top thereof to receive

and retain one side of the box cover superposed upon said one side of the box body whereby the cover will be retained to rest 10 upon the side of the box body positioned as aforesaid with extension above and in substantial continuation of said body.

CLARENCE P. JOHNSON.
